(57) CLAIM

The ornamental design for an circle pavé bead, as shown and described.

DESCRIPTION

FIG. 1 is an isometric view of a circle pavé bead showing my new design;

FIG. 2 is a front elevational view thereof;

FIG. 3 is a rear elevational view thereof;

FIG. 4 is a top plan view thereof;

FIG. 5 is a side elevational view thereof;

FIG. 6 is a bottom plan view thereof; and,

FIG. 7 is an opposite side elevational view of FIG. 5.

The broken lines showing holes in FIGS. 1, 5 and 7, star logos in FIGS. 1, 2, 4, 5, 6 and 7 and the diamond in FIG. 3 in the drawings represent portions of the pavé bead which form no part of the claimed design.
